UNITED STATES PATENT OFFICE.

HENRY RUPPEL, OF CLEVELAND, OHIO, ASSIGNOR TO AMERICAN STOVE COMPANY, OF ST. LOUIS, MISSOURI, A CORPORATION OF NEW JERSEY.

WICK-BURNER AND WICK.

1,146,658.

Specification of Letters Patent. Patented July 13, 1915.

Application filed October 9, 1913. Serial No. 794,262.

To all whom it may concern:

Be it known that I, HENRY RUPPEL, a citizen of the United States, residing at Cleveland, in the county of Cuyahoga and 5 State of Ohio, have invented certain new and useful Improvements in Wick-Burners and Wicks, of which the following is a specification, reference being had therein to the accompanying drawing.

10. My invention relates to improvements in wick burners and wicks, the primary objects of which are to provide a burner and a wick in which the top or burning portion of the wick is readily renewable.

15. The present invention pertains particularly to the annular type of burner and wick for use in heating and cooking stoves. It is well-known to those skilled in this art that in this type of burner the wick is quickly 20 carbonized and charred by reason of the high heat at the exposed portion of the wick and immediately at the upper ends of the wick tube. By reason of this charring and carbonizing of the wick it is necessary to 25 frequently remove the charred and carbonized portion and the wick is of short life and must be removed and another put in position in the burner. The removal of the wick is a disagreeable task by reason of the 30 oil contained thereon and it is a difficult task, especially for the housewife or servant.

It is one of the objects of this invention to prevent the necessity for removing the wick from the burner by providing a renew- 35 able top or burning portion for the wick, said top or burning portion being readily removable and a new one readily put in its place.

A further object of the present invention 40 is to so construct the wick and burner that the removable top or burning portion thereof is prevented from being displaced when the wick is lowered for extinguishing it or turning it low and to cause the movable or loose 45 burning portion or top to firmly contact with the cotton portion of the wick so as to insure good capillary action from the wick to the renewable top or burning portion.

In the accompanying drawing—Figure 1 50 is a perspective view of the base of a burner showing my improved wick applied thereto. Fig. 2 is a vertical sectional view of Fig. 1. Fig. 3 is a vertical sectional view of a portion of the improved wick. Fig. 4 is a detached perspective view of the removable

and detachable top or burner portion of the wick. Fig. 5 is a perspective view of a modified form of the removable and detachable top or burner portion of the wick.

Referring now to the accompanying drawings, 1 is an outer wick tube and 2 the inner wick tube which, in the form here shown, is of the Argand type. The chimney portion of the burner is omitted, as that forms no part of my present improvement. The 60 burner may be of any desired type and especially of the Argand or annular type.

My improved wick comprises a lower cotton wick 3, of the ordinary form. Secured to the outer side of the upper end of this cotton wick is an annular perforated plate 4, which extends a short distance beyond the end of the wick and secured to the inner wall of the cotton wick, at its outer end, is a perforated plate 5, which extends a corresponding distance beyond the cotton wick. The extending portions of the perforated plates 4 and 5 form between them an open top pocket 6, and in this pocket is removably placed a ring 7. This ring 7 is preferably formed of studs and is of a size to fit within the pocket 6, sufficiently loose to be readily removable therefrom. The cotton wick 3 carries the usual perforated raiser plate 8, so that the wick is vertically 85 movable between the wick tubes 1 and 2.

In the type of burner here shown, the wick is limited in its upward movement by suitable stops 9, which project outward from the inner portion of the burner in the path of travel of the wick to limit the upward movement thereof and marks the maximum of the upward movement of the wick. As stated, the removable burner portion 7 of the wick is of a size to be readily placed in the pocket 6, and in order to hold this removable portion 7, in the cup when the wick is lowered, the outer wall 4 is provided with a suitable number of upwardly and slightly inwardly extending arms 10, which can be moved laterally if necessary when a new wick top or ring 7 is placed in position. The stop arms 9, as here shown, are attached to a diaphragm 11, which is carried by a removable spider 12, so that this member 105 and the arms 9 are removable when it is desired to remove the top portion 7 of the wick, and to put in position a new wick top or ring. After the new wick top or ring 7 is put in position the diaphragm 11, with 110

its arms 9, are then screwed in the position shown in Figs. 1 and 2.

It is essential that the removable and renewable burning portion 7 of the wick 5 should have its lower edge in close contact with the upper edge of the cotton wick 3, when the wick is raised and in its burning position, so that the oil will be sure to flow from the cotton wick into 10 the removable part 7 by capillary action, the required contact between the removable portion 7 and the cotton wick insured by the stops 9 engaging the top edge of the removable portion when the wick is 15 turned up and forcing it down into the cup in contact with the top edge of the wick 3. After the burner has been in operation some time and some carbon formed on the wick, these stops are liable to adhere to some extent by the baking action to the upper edge of the removable portion 7, and when the wick is lowered will have a tendency to pull it out. These stops 9 are prevented from holding the removable portion 7 when the 20 wick is lowered by the arms 10, which holds the portion 7 within its cup or receiver.

Fig. 4 shows a removable and detachable burner portion 7, constructed of asbestos only, whereas Fig. 5 shows a removable and 30 attachable burner portion 7', formed of outer and inner mica walls 13 and 14, and an inner filling of asbestos 15.

This improved construction avoids the necessity of disassembling any part of the 35 burner for the removal of the wick to put a new wick in place, as is required in burners of this type, by providing a wick with a renewable top or burner portion, which can be readily put in position or removed therefrom without attempting to remove that portion of the wick which extends down into an oil font or reservoir. It avoids the 40 disagreeable task of handling the oily wick and oftentimes a difficult task of getting the old wick out and of properly putting a new wick in. The improvement also insures that the renewed portion of the wick shall remain in position and also have proper capillary contact with the cotton wick and at the 45 same time enables the top portion of the wick to be quickly and conveniently renewed.

With an improvement of this character,

the housewife or servant can renew the burner portion of the wick frequently and 55 with perfect convenience and ease, thus keeping the burner cleanly and in condition to get the best results. These renewable portions of the wick will be many times less expensive than the new wicks and obviate the 60 difficult task of removing the old wick and putting a new one in.

Having thus described my invention, what I claim and desire to secure by Letters 65 Patent is:

1. The combination with a burner and its wick tubes, of a vertically movable wick between the tubes, the wick having a projecting open top pocket at its upper end adapted to pass between the wick tubes when the 70 wick is lowered, a burning tip having a substantial and permanently formed contour adapted to loosely fit the said pocket and removable from and replaced within the 75 said pocket, stationary arms projecting over the path traveled by the wick to engage the upper edge of the said removable loose portion when the wick is elevated to depress the removable portion in contact with the wick, and one of the walls of the pocket 80 having upwardly projecting arms engaging the removable portion to hold it within the pocket when the wick is lowered.

2. The combination with a burner and its wick tubes, of a vertically movable wick 85 between the tubes, the wick having at its upper end an open top pocket adapted to pass between the wick tubes, and a burning tip of permanent and substantial contour corresponding with the contour of the 90 pocket and of a size to removably fit therein, one wall of the wick tube supporting arms which project outward in the line of travel of the wick and in a vertical plane above the upper end of the wick tubes for 85 the purpose described, and the wall of the pocket provided with inwardly extending means laterally movably engaging the said removable burning tip for the purpose described.

In testimony whereof I hereunto affix my signature in the presence of two witnesses.

HENRY RUPPEL
